UNITED STATES PATENT OFFICE.

GEORGE L. WELLER, OF ELYRIA, OHIO, ASSIGNOR TO NATIONAL TUBE COMPANY, A CORPORATION OF NEW JERSEY.

BOILER.

Application filed April 16, 1927. Serial No. 184,329.

This invention relates to boilers and more particularly to waste-heat boilers and has for one of its objects the provision of a boiler construction which will utilize the maximum amount of heat from the gases passing therefrom.

Another object is to provide a boiler which will give a maximum and steady supply of dry steam.

10 A further object is to provide a boiler in which the scale deposit will be reduced to a minimum, thereby resulting in higher efficiency.

In the drawings—

15 The figure shows a vertical section through a boiler constructed in accordance with this invention.

Referring more particularly to the drawings, the letters A, B, and C designate the 20 banks of boiler tubes which are supported in the heating chamber 2. The banks of tubes A and B are inclined from front to back of the chamber 2 and are connected at the front and back ends by the usual tube 25 headers 3 and 4, respectively. A combined expansion and steam drum 5 is mounted above the rear end of the upper bank of tubes A at a level above the highest point of the bank of tubes A and is connected to 30 the tube headers 3 and 4 by tubes or pipes 6 and 7, respectively, so as to provide for circulation through the tubes to and from said drum. A manifold drum 8 is also mounted below and connected with the headers 3.

35 The heating chamber 2 is divided intermediate the front and back walls of the boiler structure by a vertically disposed baffle wall 9, into primary and secondary heating zones X and Y, respectively.

40 The primary heating zone X has its lower end closed by a wall 10 while the secondary heating zone has its lower end open and in communication with an outlet passageway 12 for the waste-heat gases, which passageway communicates with a stack flue 13 through which the gases are drawn by the stack draft or by an induced draft fan (not shown) as desired.

45 The bank of tubes C are disposed in the outlet passageway 12 and are inclined from back to front of the passageway and have their front and back ends connected by the usual tube headers 14 and 15, respectively.

55 The headers 15 are connected with the head-

ers 4 so as to provide for passage of the water and steam from the tubes of the bank C with the banks A and B.

The headers 14 are connected at their lower end with a feedwater and blow-off drum 16, which is connected to a feedwater line (not shown) and has blow-off tubes 17 which connect with a pipe 18 leading to a blow-off vent (not shown).

A waste-heat flue 19 opens through a port 65 into the lower end of the primary heating zone X.

The waste-heat gases enter the zone X of the chamber 2 and, due to the baffle wall 9, are compelled to pass upwardly around the 70 front half of the banks of tubes A and B and then downwardly around the rear half of the banks of tubes A and B in the zone Y. The gases then enter the outlet passageway 12 and flow forwardly in said passageway 75 the full length of the bank of tubes C and enter the stack flue 13.

The cold feedwater enters the forward or low end of the bank of tubes C through the drum 16 which is at the point of exit of 80 the waste-heat gases, so that the cold water will extract the maximum of heat from the gases and the water is heated to a material degree before entering the tubes in the heating chamber 2, thus giving a maximum output of steam from the boiler.

By admitting the feedwater to the lower end of the bank of tubes C as above described, the scale deposit in the tubes is held to a minimum since the feedwater is heated 90 in the bank of tubes C to a point where the scale forming solids are precipitated in the tubes C where the temperature is low enough to prevent adhering to the tubes and is carried away through the blow-off tubes 17.

95 While I have shown and described one specific embodiment of my invention it will be understood that I do not wish to be limited thereto since various modifications may be made without departing from the scope of 100 my invention, as defined in the appended claim.

I claim—

A waste-heat boiler comprising a heating chamber, a plurality of banks of tubes inclined from front to back of said chamber, tube headers connecting the tubes of said banks at each end, an expansion and steam drum above said banks of tubes, means connecting said headers with said expansion and 105 110

steam drum, a baffle wall extending vertically in said heating chamber intermediate the front and back walls of said chamber so as to divide said chamber into primary and secondary heating zones, an inlet for the waste-heat gases communicating with said primary heating zone, an outlet passageway for the waste-heat gases communicating with said secondary heating zone, a bank of tubes extending longitudinally of and inclined from back to front of said outlet passageway, tube headers connecting the rear ends of the tubes of said last bank and communicating with the tube headers con-

necting the rear ends of the tubes of said first named banks of tubes, other tube headers connecting the forward ends of the tubes of said last named bank of tubes, a combined feedwater and blow-off drum communicating with all of the tube headers connecting the forward ends of the tubes of said last named bank of tubes, and a stack flue communicating with said outlet passageway below the forward end of said last bank of tubes.

In testimony whereof, I have hereunto signed my name.

GEORGE L. WELLER.
